CLAIM

The ornamental design for a bike rack as shown and described.

DESCRIPTION

FIG. 1 is a top, front and left side perspective view of a bike rack showing my new design;

FIG. 2 is a top, rear and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is an enlarged view of portion 9 in FIG. 1.

The evenly dashed broken lines in FIGS. 1-9 illustrate portions of the bike rack that form no part of the claimed design.

The unevenly dashed broken lines in FIGS. 1 and 9 illustrate the boundary of the enlarged view and form no part of the claimed design.

1 Claim, 9 Drawing Sheets
